UNITED STATES PATENT OFFICE.

ADELL DELMAR ALBRECHT, OF GREENVILLE, ILLINOIS.

PAPER AND LETTER HOLDER.

No. 895,324.

Specification of Letters Patent.

Patented Aug. 4, 1908.

Application filed January 16, 1908. Serial No. 411,194.

To all whom it may concern:

Be it known that I, ADELL D. ALBRECHT, a citizen of the United States, and a resident of Greenville, in the county of Bond and State 5 of Illinois, have invented a new and Improved Paper and Letter Holder, of which the following is a full, clear, and exact description.

This invention relates to devices for holding newspapers, letters and similar articles.

16 The object of the invention is to produce a device of this class which is simple in construction and which can be readily mounted upon a wall or post for the purpose stated.

More specifically, the object of the invention 15 is to construct the device so that it can be economically manufactured. To this end, the body of the device is of special construction, which adapts it for being formed of stamped sheet metal.

20 Further objects of the invention will appear more fully hereinafter.

The invention consists in the construction and combination of parts to be more fully described hereinafter and particularly set forth 25 in the claims.

Reference is to be had to the accompanying drawings forming a part of this specification, in which similar characters of reference indicate corresponding parts in both figures.

30 Figure 1 is a front elevation of the device, representing the same as attached to a door jamb, and showing how it operates to hold a number of letters; and Fig. 2 is a side or edge elevation of the device.

35 Referring more particularly to the parts, 1 represents the body of the device, which consists of a wall plate which may have the form indicated. This plate is preferably elongated horizontally, and is attached to a door

40 jamb or post 2 by means of suitable holding devices such as the screws 3. The upper edge of the plate projects upwardly and is crimped so as to form a horizontal sleeve 4. The ends of the plate are bent outwardly and 45 then inwardly so as to form hooks 5, which hooks present bills 6 projecting inwardly. The ends of these bills 6 lie near the face of the door jamb, as indicated most clearly in Fig. 2. These hooks 5 operate as guides in a

50 manner which will appear more fully hereinafter. The plate 1 affords means for holding the arm 7 of the holder. This arm presents two upwardly extending parallel bars 8, which are bent outwardly at their upper ends, 55 as illustrated in Fig. 2, and connected by a cross bar or handle 9. The two bars 8 and

the handle 9 are formed integrally with each other, as shown. The bars 8 extend downwardly between the face of the door jamb 2 and the hooks 5, and are formed at their 60 lower ends into resilient coils 10.

The arm 7 is adapted to be formed of stout resilient wire. This wire beyond the coils 10, is bent upwardly and slightly inwardly, so as to form shanks 11, and the ends of these 65 shanks are bent inwardly in alinement with each other so as to form wrists or pivot pins 12, which are received in the ends of the sleeve 4, as shown.

Attention is called to the fact that the upper ends of the bars 8, where they are bent outwardly as suggested above, are formed so as to present curved guide lips 13. These guide lips operate as efficient guides in assisting the placing of the letters 14 in the 75 holder, the said letters being pushed downwardly in a horizontal position so that the force of the springs 10 pressing the bars 8 upon the face of the letters, holds them against the face of the door jamb, as will be 80 readily understood.

Special attention is called, also, to the fact that the coils 10 are disposed at a considerable distance from the body of the letters or papers held in the holder. This is a highly 85 advantageous arrangement, as it operates to maintain the bars 8 in substantial parallelism with the face of the door jamb as the number of letters or papers increases. This prevents the bars from exerting a great pressure at a single point, which might tend to 90 rumple or fold the letters or papers. In this connection, attention is drawn, also, to the fact that the coils themselves are not attached to the face of the door jamb, so that 95 they can be displaced outwardly when the number of letters or papers increases.

From this arrangement it should be understood that the upper portion of the bars 8 will lie flat upon the outer faces of the package of papers or letters, and the coils will be displaced outwardly so as to adapt themselves to this position of the arm 7. As the number of papers or letters increases, the arm 7 is, of course, forced outwardly. The 105 hooks 5 then operate as guides for the bars 8. The bar 9 operates as a handle to facilitate the removal of letters or papers when desired.

It will be evident that the wall plate 1 can 110 be readily stamped from sheet metal by the well known stamping process, and the device

is very simply made and economical of material.

Having thus described my invention, I claim as new and desire to secure by Letters

5 Patent:

1. In a device of the class described, in combination, a plate adapted to be fixed to a support and having extensions constituting guides at the ends thereof, an arm having oppositely disposed bars disposed adjacent to said respective guides and guided thereby; said arm having resilient coils and shanks therebeyond, said shanks having their ends attached to said plate.
- 10 2. A device of the class described, comprising a plate having a transverse sleeve and guides formed at the ends thereof, an arm presenting oppositely disposed bars passing downwardly through said guides and having resilient coils formed at the lower ends thereof, and shanks formed beyond said coils, said shanks having wrists mounted in said sleeve.
- 15 3. A device of the class described, comprising a wall plate having a transverse sleeve, and guide hooks formed at the ends thereof, an arm presenting oppositely disposed bars extending vertically downward through said guide hooks respectively, and having resilient
- 20 30 coils formed at the lower ends thereof, shanks beyond said coils having pivots received in

said sleeve, the upper ends of said arms being bent outwardly to form curved guide lips, and a transverse bar connecting the upper ends of said arms and offset outwardly from the plane thereof.

4. A device of the class described, comprising a wall plate having a transverse sleeve on the upper edge thereof, and guide hooks formed at the ends thereof, said guide hooks being offset outwardly, and having bills projecting inwardly toward the plane of said wall plate, an arm having oppositely disposed parallel bars extending downwardly through said hooks and having coils formed at a point below said hooks, said coils having shanks formed therebeyond extending upwardly, said shanks having pivots formed thereon received in the ends of said sleeve, the upper ends of said arms having outwardly curved guide lips, said arms being connected beyond said guide lips by a transverse bar offset outwardly from the plane thereof.

In testimony whereof I have signed my name to this specification in the presence of two subscribing witnesses.

ADELL DELMAR ALBRECHT.
